**SCORED BLANK FOR DISPLAY OR
INSULATION USE**
John Scherotto, Union City, N.J.
(353 W. 57th St., New York, N.Y.)
Filed Feb. 27, 1959, Ser. No. 796,158
6 Claims. (Cl. 41—10)

This invention relates to a scored, sheet blank; and more particularly, concerns a blank scored and slit to a predetermined pattern for conversion into a three dimensional article suitable for a number of purposes.

An object of this invention is to provide a sheet blank scored and slit; the blank being convertible by a folding operation which brings opposite marginal portions thereof toward each other, into a three dimensional article distinguished by parallel rows of pyramidal protuberances or projections.

A further object of this invention is to provide a foldable blank of the character described which is convertible into articles useful for ornamental, display, cushioning or insulation purposes.

Still another object of this invention is to provide a blank of the character described, which is foldable along parallel lines into compact form for shipping or storage purposes, yet may be expanded to provide rows of pyramidal projections with interposed cut outs, the dimensions of the projections and cutouts being adjustable in accordance with the extent of expansion, to produce varied ornamental effects.

Yet another object of this invention is to provide an improved ornamental device distinguished by rows of pyramidal projections and in the form of a simulated Christmas tree, wherein the projections by reason of their relative disposition give rise to distinctive optical effects.

Other objects of this invention will in part be obvious and in part hereinafter pointed out.

In the drawing,

FIG. 1 is a plan view of a portion of a scored and slit blank embodying the invention;

FIG. 2 is a plan view of a portion of said blank in partially folded form;

FIG. 3 is a plan view of an ornamental article derived from the blank shown in FIG. 1; and

FIG. 4 is a transverse, sectional view showing the blank in compactly folded, packaged form.

Referring in detail to the drawing, 10 designates a flat sheet blank embodying the invention. The same may be of cardboard, pasteboard, metal foil faced board, plastic sheeting or other suitable material which lends itself to scoring, slitting and folding operations.

The blank 10 may be rectangular in shape with a front surface 11. The blank 10 is scored on its rear surface along parallel, equally spaced lines to form parallel fold lines 12 on the front surface 11 thereof. Such fold lines 12 may also be parallel to the lateral marginal portions of the blank, the right hand marginal portion being shown at 13 in FIG. 1. The blank 10 is thus subdivided into longitudinal portions in the form of laterally adjacent rows indicated at 14, 15, 16, 17 and 18.

Each of the rows 14 to 18 is transversely slit at uniform intervals as at 19; the slits 19 in adjacent rows being in staggered relation, the slits in alternate rows being in transverse alignment. Thus, each pair of fold lines 12 and the intersecting pair of slits 19 define a quadrilateral blank portion 20 which may be square in shape as indicated in FIG. 1, or may be rectangular.

Each blank portion 20 is scored on its front surface 11 along diagonal intersecting lines 21, 22 to provide corresponding fold lines on the rear surface of said blank. Score lines 21, 22 terminate at their opposite ends at the intersection of slits 19 and fold lines 12. The intersec-

2

tion of each set of score lines 21, 22 provides an apex for a pair of laterally related triangular blank portions 23 and a pair of longitudinally related, similar triangular blank portions 24.

5 The blank 10 is further scored on its rear surface along longitudinally extending parallel lines to provide parallel fold lines 25 on the front blank surface 11; such fold lines 25 passing through the apex portions of the triangular blank portions 23, 24 in each of the rows 14 to 18.

10 The scored and slit blank 10 may be converted into a three dimensional article by folding the same along fold lines 12 to move the opposite marginal portions 13 toward each other. Such folding operation will cause each of the blank portions 20 to assume a pyramidal shape due to the folding action along the lines opposite diagonal score lines 21, 22. Furthermore, the triangular blank portions 24 will be inwardly pleated along fold lines 25.

15 As a consequence of such folding operation, folded blank 10 will exhibit rows of pyramidal protuberances or projections with inward pleats on two faces thereof; the same being spaced in their respective rows by quadrilateral openings 26 derived from slits 19. It will be apparent, that the altitude of each pyramidal projection will be determined by the extent of the movement of the lateral blank margins 13 toward each other, with a corresponding variation in the shape of openings 26. Thus, as the altitude of the pyramidal projections increase, the spacing between the laterally related apices of openings 26 decrease.

20 The blank 10 in its 3 dimensional form may be used as a display backing or base, having a distinctive ornamental appearance due to the pyramidal projections. This is particularly true when the front face 11 of the blank is formed of bright metal foils. Also, such three dimensional article may be used as cushioning material in packing various items of fragile or semifragile nature. Furthermore, the combination of projections and openings make the article useful as acoustic insulation for walls and ceilings.

25 The blank may also be manipulated in a particular manner to produce simulated Christmas trees, as indicated in FIG. 3. In this case, the marginal edge portions 13 of the blank are brought together as close as possible, with the intervening folded blank portions in close surface contact with each other. A fastening element 27 such as a ring or staple holds the constricted end portions 28 of the folded blank, together. The opposite end portion of the blank is permitted to fan out, thereby producing a triangular shaped article in which the progressively changing variation in dimensions and shape of the projections and 30 openings in each row results in unique optical effects.

35 The blank 10 may be folded and compressed into compact form for packaging, shipping and storage, as indicated in FIG. 4. The blank 10 is closely folded along the fold lines 11 to reduce the same to a bar shape which may be 40 conveniently inserted into packages of corresponding section as indicated at 29.

45 As various changes might be made in the embodiments of the invention as shown, without departing from the spirit thereof, it is understood that such embodiments as 50 shown are to be deemed as illustrative and not limiting except as set forth in the appended claims.

Having thus disclosed my invention, I claim as new and desire to protect by Letters Patent:

55 1. A folded and slit flat sheet blank in folded form providing an article having opposed marginal portions movable towards and away from each other, said article having a plurality of hollow rows of pyramidal projections between said marginal portions, each of said projections comprising a pair of laterally related triangular portions 60 and a pair of longitudinally related triangular portions having a common apex, each of the longitudinally related triangular portions being pleated along a line extending

from said apex to the base thereof, the projections in adjacent rows being in staggered relation, successive projections in each row being separated by a quadrilaterally shaped opening in said blank, the altitude of each projection decreasing and the lateral dimension of each opening increasing upon displacement of said marginal portions from each other.

2. A sheet scored on one surface thereof along parallel lines to provide equally spaced, parallel fold lines on the other surface of said sheet and slit to provide equally spaced slit lines extending transversely of said fold lines, said slit lines being arranged in rows defined by adjacent pairs of fold lines, the spacing between slit lines being equal to the spacing between fold lines, the slit lines in adjacent rows being in staggered relation and the slit lines in alternate rows being in transverse alignment, each pair of slit lines in a given row intersecting the fold lines of said row, and defining a square sheet portion, each of said sheet portions being scored on said other surface of said sheet to provide a pair of intersecting diagonal fold lines on said one surface of the sheet extending to the ends of said pair of slit lines and said sheet being scored on said one surface thereof to provide a single fold line on the other surface of the sheet passing through the intersection of said diagonal fold lines and being parallel to said fold lines, said sheet being foldable to a reduced transverse dimension along said parallel fold lines whereby each sheet portion is converted to a substantially pyramidal form projecting from said other surface of said sheet and having an apex corresponding to the intersection of the diagonal fold lines thereof and opposed, inwardly pleated portions defined by said single fold line, the successive pyramidal sheet portions in each row being longitudinally separated by quadrilateral openings formed from said slit lines.

3. A rectangular sheet having a plurality of parallel rows of adjacent substantially pyramidal hollow protuberances extending parallel to the side edges of said sheet, the protuberances in adjacent rows being in staggered relation, the protuberances in alternate rows being in transverse alignment, each protuberance having a pair of laterally related triangular shaped, planar faces disposed parallel to the side edges of said sheet and a pair of longitudinally related, triangular shaped, inwardly pleated faces disposed parallel to the end edges of said sheet, the pleated portions of the protuberances in each row being in longitudinal alignment, the successive protuberances in each of said rows being separated by quadrilateral openings in said sheet.

4. A flat sheet blank convertible into a three dimensional article, said blank being scored on the rear surface thereof to provide on the front surface thereof longitudinally extending, parallel fold lines, said blank being scored on the front surface thereof to provide a plurality of longitudinally extending, adjacent sets of intersecting diagonal fold lines on the rear surface thereof extending

between each pair of adjacent longitudinal fold lines, each of said diagonal fold lines terminating at said longitudinal fold lines, the sets of intersecting diagonal fold lines in laterally adjacent pairs of longitudinal fold lines being in staggered relation, said blank being slit to provide each set of diagonal fold lines with a pair of parallel slit portions interconnecting the laterally opposed ends of said diagonal fold lines respectively, said blank being scored on the rear surface thereof to provide each set of intersecting diagonal fold lines with a fold line on the front surface thereof extending from the intersection of said diagonal fold lines to said slit portions, whereby said blank may be folded on said longitudinal fold lines to bring the lateral edges of said blank toward each other, thereby causing each blank portion between adjacent slit portions to fold into a hollow substantially pyramidal shape along said intersecting pairs of diagonal fold lines with pleated face portions extending to openings formed by said slit portions.

20 5. A rectangular decorative sheet scored to provide a plurality of adjacent fold lines forming a plurality of rows of substantially pyramidal hollow protuberances projecting from the front surface thereof and extending parallel to the side edges of said sheet, the protuberances in adjacent rows being in staggered relation to each other, the protuberances in alternate rows being in substantially transverse alignment with each other, the successive protuberances in each row being separated from each other by quadrilaterally shaped openings formed in the sheet.

25 6. A decorative sheet as in claim 5 wherein said fold lines provide longitudinally extending pleated sheet portions, said pleated portions being gathered together at one end of said sheet, and means for holding the gathered pleated portions together whereby to taper the pleated portions toward said one end of the sheet, the pleated portions being in relatively displaced relation at the other end of the sheet.
